DESIGN FOR A SEED ENVELOPE

Walter L. Earnshaw, Hollywood, Calif.

Application March 9, 1938, Serial No. 75,696

Term of patent 3½ years

To all whom it may concern:

Be it known that I, Walter L. Earnshaw, a citizen of the United States, residing at Hollywood, in the county of Los Angeles, State of California, have invented a new, original, and ornamental Design for Seed Envelopes, of which the following is a specification, reference being had to the accompanying drawing, forming part thereof.

In the drawing, showing my new design:

Fig. 1 is a front view of a seed envelope having a colored transparent window through which seeds, contained in the envelope may be seen; and,

Fig. 2 is a sectional view thereof taken on the line 2—2 of Fig. 1.

I claim:

The ornamental design for a seed envelope, substantially as shown.

WALTER L. EARNSHAW.
